Application May 16, 1950, Serial No. 162,213

14 Claims. (Cl. 192—131)

1

My invention relate to presses for shaping blanks by use of cooperating dies, the press having provision for causing the press head to be normally maintained in such position as to cause the dies to be separated so that the blank may be inserted between them, the press also having operator actuated control means which when actuated causes the press head to move through its working stroke to close the dies and then return to its normal position and stay there until the control means is again actuated. The invention particularly relates to the provision of means for insuring against the possibility of the operator having either of his hands between the dies during the working stroke of the press head and for preventing the press from accidentally making the working stroke when it is not desired to have it do so.

In the drawings:

Fig. 1 is an elevation of a press according to 20 the invention, with parts omitted;

Fig. 2 is a side elevation of the press according to Fig. 1, with parts omitted;

Fig. 3 is a schematic diagram of the apparatus for operating and controlling the press; and

Figs. 4 to 8 inclusive show across the line diagrams of the electric circuit connections according to Fig. 3 with the parts in different operative position, respectively, these figures also showing a control switch for the press, and the press cylinder and its distributing valve, in different operative positions corresponding to the positions of parts in these across the line diagrams.

Referring particularly to Figs. 1, 2 and 3, the press comprises the base 1 on which is mounted a supporting frame 3. On this frame is reciprocally mounted a vertically moving press head 5, the latter carrying a die part, conventionally shown at 7, which part cooperates with a second die part, conventionally shown at 9, carried by the base of the press. For reciprocating the press head is shown a piston 11 mounted for reciprocation in the vertical cylinder 13 carried by the frame of the press, the piston rod 15 connecting the piston to the press head so that when the piston is reciprocated the press head will reciprocate with it.

In the embodiment of the invention shown an operator controlled reciprocating distributing valve 17 of the piston type, fitting the bore of the valve casing 19 (Figs. 2 and 3) in a fluid tight manner, is provided for controlling the reciprocations of the piston 11. Normally this valve is maintained at the left hand end of its travel, as viewed in Fig. 3, for admitting pressure fluid from a source of supply to the lower end of the cylinder and for connecting the upper end of the cylinder to exhaust so as to maintain the press head at the upper end of its stroke for holding the two die parts in separated relation. By the operator causing the valve to move to the 50

right hand end of its travel pressure fluid will be admitted to the upper end of the cylinder while the lower end of the cylinder will be connected to exhaust for causing the piston to make a downward stroke for closing the die parts. In the embodiment of the invention illustrated when the piston reaches the lower end portion of its stroke the valve is automatically shifted to the first mentioned end of its travel, causing the piston to move to the upper end of its stroke and to be maintained therein until the operator again causes the valve to move to the right hand end of its travel.

In the present embodiment of the invention, 15 for casing the distributing valve to move to that end of its travel which causes the press head to make its downward stroke, a pair of push buttons 21 and 23 are provided, each of these push buttons being of a common type in respect to the switch part thereof being biased into open position by a compression spring or the like (not shown) so that the switch part will automatically open upon the push button being released by the operator. The circuit connections are 25 such that both push buttons must be depressed to close them before the controlling valve can be so moved. Also the push buttons are positioned far enough apart so that the operator must employ both hands to depress them. The 30 circuit connections are further such that after the piston makes a downward stroke both the push buttons must be released by the operator before the distributing valve can be shifted out of its normal position to cause the press head to make a second downward stroke.

In normal operation the operator dips the blank in a so-called "drawing compound" which is commonly an oily liquid and then places it on the lower die part 9 with the press head at the upper end of its stroke. He then depresses both push buttons to cause the press head to make its downward stroke, the press head automatically returning to the upper end of its stroke after it has operated upon the blank to shape it, whereupon the operator removes the finished work from the lower die and places a new blank thereon. The time it takes for the press head to make its downward stroke, and the placing of the push buttons a considerable distance from the path of travel of the upper die part, make it next to impossible for the operator to get either of his hands between the dies while the downward stroke of the press head takes place. Furthermore, because both push buttons must be permitted to open before the press head can make a second downward stroke, the press is rendered inoperative in case either push button becomes short circuited or fails to open upon being released.

Heretofore, when it was attempted to control the press by a pair of push buttons, the circuit

connections were such that if one push button became short circuited, say by the drawing compound seeping into it, or became mechanically defective so that it would not open when released, neither of these circumstances would be discovered until the other push button became short circuited or defective, in which case when said other push button became short circuited or defective the press would repeat its downward stroke and in some instances while the operator had his hands between the dies in inserting the blank or removing the finished work, with very distressing results. Still further, when heretofore attempting to control a press by a pair of push buttons, it was possible for the operator to prop one push button in depressed position and operate the press by use of the remaining push button, thus leaving one of his hands free to manipulate the blank, with the result that if the last mentioned push button became short circuited the press would repeat its downward stroke and sometimes while the operator had his free hand between the two die parts, again with distressing results. All these possibilities of the press accidentally repeating its downward stroke are eliminated by the present invention.

As indicated in Figs. 1, 2 and 3, an electric motor 25 is provided for driving a pump 27, the motor, as shown, being energized by the line having the leads 29, in which line is conveniently interposed a suitable switch or starter (not shown) for establishing and interrupting operation of the motor as desired. When the press is in operation normally the motor will be continuously operated. Conveniently the motor and pump are mounted on the frame of the press as shown by Figs. 1 and 2.

As diagrammatically shown by Fig. 3, the pump 27 has an inlet or suction pipe 31 in communication with an oil tank or sump 33 so that the pump will draw oil from said tank and discharge it under pressure into the outlet pipe 35 of the pump. Excess pressure in the outlet pipe may be prevented by use of a pressure relief valve 37 in a pipe 39 connecting the outlet pipe to the oil tank 33.

The outlet pipe 35 of the pump 27, as shown by Fig. 3, opens into the distributing valve casing 19 through a port 40 midway the length of that casing. Near one end the valve casing has an exhaust port 41 connected by a pipe 43 to the oil tank 33. Near its opposite end it has a second exhaust port 45 connected by a branch pipe 47 to the pipe 43. As further shown, the valve casing has a port 49 operatively positioned between the ports 40 and 45, which port 49 is connected by a pipe 51 to the upper end of the cylinder 13, and has a further port 53 operatively positioned between the ports 40 and 41, which port 53 is connected by a pipe 55 to the lower end of the cylinder. The distributing valve 17, as shown, is provided with the spaced annular grooves 57 and 59. When the valve is in its position shown by Fig. 3 the groove 57 will connect the inlet port 40 to the port 53 to admit pressure fluid from the pump through the pipe 55 to the lower end of the cylinder, while the groove 59 will connect the port 49 to the port 45 to connect the pipe 51 to the exhaust pipe 47 so as to exhaust the upper end of the cylinder and thus maintain the piston and press head at the upper ends of their strokes. When the valve is shifted to the opposite end of its travel, as shown for example in Fig. 6, the groove 59 will connect the inlet port 40 to the port 49 to admit pressure fluid

from the pump through the pipe 51 to the upper end of the cylinder, while the groove 57 will connect the port 53 to the port 41 to connect the pipe 55 to the exhaust pipe 43 so as to exhaust the lower end of the cylinder and thus cause the piston to make a downward stroke. After the piston reaches the end of its downward stroke shifting of the valve from its position shown by Fig. 6 to that shown by Fig. 3 will cause the piston 10 and press head again to return to the upper ends of their strokes where they will remain until the operator again causes the valve to shift to its position shown by Fig. 6.

As illustrated, the distributing valve 17 is 15 shifted to the end of its travel opposite that shown in Fig. 3 by the operator causing a solenoid 61 to be energized for drawing into the solenoid an associated armature 63. This armature is shown as connected by a rod 65 to one end of a lever 20 67 (Figs. 2 and 3) pivoted intermediate its length, at 69, to a stationary bracket 71 carried by the frame of the press, the opposite end of this lever being connected by a link 73 to the outer end 25 of one arm of a bell crank lever 75, the outer end of the other arm of the bell crank lever being pivotally connected to the valve stem 77, while the bell crank lever adjacent the juncture of its two arms is swingingly connected by a link 79 to the valve casing 19. Cooperating with the armature 30 63 is a compression spring 81 which normally holds the valve in its position shown by Fig. 3, the solenoid 61 when energized drawing the armature 63 downward, as viewed in Fig. 3, against the upwardly exerted force of this spring so as to 35 shift the valve.

For energizing the solenoid 61 so as to shift the distributing valve 17 to the right as viewed in Fig. 3, and for deenergizing the solenoid to 40 permit the spring 81 to return the valve to the position shown by Fig. 3 and be maintained in that position, the terminals of the solenoid are shown as connected by leads 63 and 85 to the stationary contacts 87 and 89, respectively, of a normally open switch 90 having a further stationary contact 91 adapted to be placed in electrical communication with the contact 87 by a 45 movable contact 93, the switch also having a still further stationary contact 95 adapted to be placed in electrical communication with the contact 89 by a further movable contact 97. The contacts 91 and 95 are shown as connected by leads 93 and 99 to leads 101 and 103, respectively, which leads 101 and 103 are shown as tapped off of two of the leads 29. The movable contacts 93 and 50 97 are diagrammatically shown by Fig. 3 as carried in insulated relation to each other by a rod 105 with which cooperates a compression spring 107 for normally holding the switch in open position. For closing the switch the rod carries an 55 armature 109 with which cooperates a solenoid 111 for drawing the rod downward against the upwardly exerted force of the compression spring for closing the switch when the solenoid is energized. As diagrammatically shown, the rod 105 also carries the movable contact 113 with which 60 cooperates the contacts 115 and 117 forming a switch part which is closed when the switch part comprising the contacts 93 and 97 is closed.

For energizing the solenoid 111 of the switch 65 90, so as to cause the distributing valve 17 to move to the opposite end of its travel to that shown in Fig. 3, one terminal of the solenoid is shown as connected by a lead 119 to one side 121 of a line, the opposite side of which line is constituted by a lead 123. The leads constituting

the opposite sides of this line are shown as connected to the opposite terminals, respectively, of the secondary winding of a step down transformer 125 the primary winding of which is energized by the line formed by the leads 101 and 103. The other terminal of the solenoid 111 is shown as connected by a lead 127 to the stationary contact 129 of a switch 131 having a second stationary contact 133, which two contacts are adapted to be placed in electrical communication by a movable contact 135 when the solenoid 137 of the switch 131 is energized. The stationary contact 133 of this switch 131 is connected by a lead 139 to the stationary contact 129 of a second and similar switch 131 also having a second stationary contact 133, which two contacts 129 and 133 of the last mentioned switch also are adapted to be placed in electrical communication by a movable contact 135 when the solenoid 137 of that switch is energized. The stationary contact 133 of the left hand switch 131 of Fig. 3 is shown as connected by a lead 141 through a normally closed switch 143, lead 145, normally closed push button 147, and lead 149 to the side 123 of the line connected to the secondary of the transformer.

The push buttons 21 and 23 hereinbefore mentioned are diagrammatically shown in Fig. 3 as being of the 4-pole single-throw type, two of the poles or contacts 151 and 153 of each of which are connected by the leads 155 and 157 to opposite sides, respectively, of the line 121, 123, while the other two poles or contacts 159 and 161 of each of which are connected by the leads 163, 165 to the opposite terminals of the solenoids 137 of the two switches 131, respectively. It will be observed from the across the line diagram of Fig. 4 that connecting the push button circuits across the line in parallel and the employment of 4-pole push buttons serve to isolate each solenoid 137 from both sides of the line when the push button for energizing that solenoid is open, and that this reduces to a minimum the possibility of ground currents by-passing either push button and energizing the solenoid associated with it.

From the above it will be observed that the two switches 131 each comprising the pair of contacts 129, 133 are connected in series, and therefore that both must be closed by energization of their solenoids 137 by depression of the two push buttons 21 and 23 to complete the circuit which energizes the solenoid 111 so that the solenoid 61 will be energized to cause the valve 17 to shift to the right from its position shown by Fig. 3 to cause the press head to make a downward stroke. As hereinafter explained, the switches 131 are tripped into open position by such shifting of the valve, which tripping of said switches, if means were not provided to prevent it, would cause the solenoid 111 to be deenergized so that the spring 107 would open the switch part comprising the movable contacts 93 and 97 and return the valve to its position shown by Fig. 3 before the downward stroke of the press head was completed. For preventing such action the movable contact 113 of the switch 90 when it contacts with the stationary contacts 115 and 117 of that switch establishes a holding circuit for the solenoid 111 to keep it energized until such holding circuit is interrupted. This holding circuit is established by the lead 171 (Fig. 3) which connects the contact 115 to one terminal of the solenoid 111, and by the lead 173 which connects the opposite contact 117 to the lead 141 at the point 174. It will be observed that by these con-

nnections the holding circuit shunts the two series connected switches 131, the holding circuit being connected across the line in parallel with the push button circuits for those switches, and containing connected in series the normally closed switch 143, the normally closed push button 147, and the switch part having the movable contact 113, as more clearly shown in the across the line diagram of Fig. 6.

10 The push button 147 is of a common construction in which the switch part thereof is biased into closed position by a compression spring so that the switch part will automatically close when the push button is released. This push button is provided for interrupting the above described holding circuit at any time while the press head is making its downward stroke so that the solenoid 111 will be deenergized to cause deenergization of the solenoid 61 and thus permit 15 the spring 81 to shift the valve to its position shown by Fig. 3, with the result of causing the press head to return to the upper end of its stroke before making a complete downward stroke.

20 The switch 143 hereinbefore mentioned, as diagrammatically illustrated, comprises a lever 175 pivoted for swinging movement at 177. The lever carries in fixed relation thereto a contact 179 which cooperates with a stationary contact 181 to which the lead 145 providing part of the holding circuit is connected. The switch is normally held in closed position by a tension spring 183 connected to one end of the lever. At its end opposite the spring the lever is shown as carrying a vertically adjustable screw 185 the upper free end of which is adapted to be struck by the member 187 of insulating material carried by the press head when the latter reaches the desired extent of its downward movement. This member 187, when it so strikes the screw, will swing the lever about its pivot to move the contact 179 from engagement with the contact 181 so as to open the holding circuit, as shown in Fig. 8, and thereby cause the solenoid 61 to be deenergized to permit the spring 81 to shift the valve from the right hand end of its travel to its left hand end, as viewed in Figs. 3 and 8, to cause the press head to make its upward stroke.

25 The two switches 131 are alike except that one, as viewed in Figs. 2 and 3, is a mirror image of the other, that is to say, one is of "right" construction and the other of "left" construction. A description of one therefore will suffice for the other. As shown by Fig. 4, cooperating with the solenoid 137 of the switch is a vertically movable armature 189 having an extension 191 pivoted at 193 to a lever 195 intermediate the length of the latter. This lever 195 is pivoted at one end, at 197, for swinging movement and is held in its position shown by Fig. 4 by a compression spring 199 bearing at one end against the lever and at its opposite end against a fixed abutment 201. At its free end the lever 195 is shown as pivotally connected at 203 to one end of a link 205, the other end of which link is pivotally connected at 207 to the outer end of a lever 209. The lever 209 is pivotally connected at 211 at an intermediate portion of its length to the outer end portion of a further lever 213 swingingly pivoted at 215, the spring 199 and weight of the parts connected to the lever 209 normally causing the lever 213 to rest against a stop 217. As diagrammatically shown, the lever 213 adjacent its outer end carries at its upper side an insulating block 219, which block carries an upwardly projecting

pin 221 on which the contact 135 is slidably and loosely mounted, a light compression spring 223 surrounding the pin and bearing at opposite ends against the block 219 and contact 135, respectively, causing that contact yieldably to adjust itself against the contacts 129 and 133 when the lever 213 is swung upwardly to close the switch. As further diagrammatically shown, the switch 131 comprises a lever 225 pivoted at one end for swinging movement at 227, the opposite free end of the lever resting against the upper side of one end portion of a still further lever 229, which latter is pivotally mounted, at 231, intermediate its length for swinging movement, a compression spring 233 bearing at its lower end against the abutment 201 and bearing at its upper end against the lever 229 normally holding the outer end of that lever against a stop 235. As shown, the lever 225 has an upwardly projecting portion 237 the upper free end of which is adapted to cooperate with the notched end portion 239 of the lever 209 for a purpose hereinafter described.

When the parts are in their positions shown by Fig. 4, and the push buttons 21 and 23 are depressed for energizing the solenoids 137 of the switches 131, the armature 189 of each switch will be drawn upwardly against the resistance of the spring 199 to swing the lever 209 about its pivot 211 and cause the notched end portion 239 of that lever to contact with the upper end of the vertically projecting portion 237 of the lever 225. Under these conditions the upper end of the projection 237 acts as a fulcrum for the lever 209 to cause the latter, upon continued upward movement of the armature 189, to swing the lever 213 about its pivot 215 and move the parts into their positions shown by Fig. 5, in which positions the switch 131 is closed. The depression of both of the push buttons 21 and 23 causes both of the switches 131 to close in this way, for energizing the solenoid 111 as above explained. When the solenoid 111 is thus energized the switch part comprising the contacts 93 and 97 closes to energize the distributing valve controlling solenoid 61 also as above explained. At the same time the energization of the solenoid 111 closes the switch part comprising the contact 113 so as to establish the above described holding circuit for the solenoid 111 so as to maintain energization of the solenoid 61 upon opening of either or both of the switches 131, all of which will be clear from the across the line diagram shown by Fig. 5. When the circuit connections shown by Fig. 5 are completed the solenoid 61 shifts the valve 17 to the right hand end of its travel, as shown in Fig. 6, so as to cause the piston 11 and press head to make their downward strokes.

As shown in Fig. 2, the two switches 131 are carried by the oil tank 33 above the lever 67, which latter is swung downward for operating the valve 17 when the solenoid 61 is energized. The outer ends of the levers 229 of the two switches 131 project toward each other from the casings of those switches, and to such end of each lever is connected a chain 241, the lower ends of which chains are connected to the upper end of a tension spring 243, the lower end of this spring being connected by a wire or the like 245 to the lever 67 adjacent the pivotal connection of the rod 65 to one end of that lever. When the solenoid 61 is energized to swing this end of the lever 67 downward the connections between the lever and the two levers 229 will

pull each lever 229 downward from its position shown by Fig. 5 to its position shown by Fig. 6, the spring 243 preventing the application of an excess force to the levers 229. Such movement of the lever 229 of each switch 131 moves the upper end of the upwardly projecting member 237 of the lever 225 of that switch from under the notched end 239 of the lever 209, which will cause the lever 213 of the switch to drop and move the contact 135 downward and thus open the switch, the parts of the switches 131 then being in their positions shown by Fig. 6 if the push buttons 21 and 23 are still closed to energize the solenoids 137, or in their positions shown by Fig. 7 if the push buttons 21 and 23 are released to deenergize the solenoids 137 and permit the springs 199 to swing the lever 195 to their downward positions. It will be observed that when the switches 131 are tripped by the levers 229 neither of those switches can be closed again by depressing either of the push buttons 21 and 23 until the trip mechanism of each switch is reset by movement of the lever 229 of that switch back to its position shown by Fig. 4.

When the piston 11 reaches the downward end portion of its stroke and opens the switch 143 the holding circuit will be interrupted, as clearly indicated by the across the line diagram shown by Fig. 8. This will deenergize the solenoid 111 to permit the spring 107 (Fig. 3) to open the switch part comprising the contacts 93 and 97 for deenergizing the valve controlling solenoid 61. When the valve controlling solenoid 61 is deenergized in this way the spring 81 (Fig. 3) will move the valve 17 again to the left hand end of its travel, as shown in Fig. 8, for admitting pressure fluid to the lower end of the cylinder 13 and exhausting it from the upper end of the cylinder so as to cause the piston and press head to move to the upper ends of their strokes. The switch 143 closes during the upward stroke of the press head 5 because of the member 187 (Fig. 3) carried by the head moving out of contact with the screw 185, but, as the deenergization of the solenoid 111 when the switch 143 opened causes opening of the switch part comprising the movable contact 113, the solenoid 111 will not be reenergized by such closure of the switch 143 until each push button 21 and 23 is released and again depressed for closing the switches 131. In these connections it will be noted that when the spring 81 swings the left hand end of the lever 67 upward the compression spring 233 of each switch 131 will move the lever 229 of that switch to its position shown by Fig. 8, so that when the push buttons 21 and 23 are again depressed by the operator upon the piston reaching the upper end of its stroke the upper end of the portion 237 of each lever 225 will be in position to cooperate with the notched end of the associated lever 209.

Also it will be noted from Fig. 6, which indicates the push buttons 21 and 23 in closed position and the piston making a downward stroke, that although by opening the push button 147 the valve 17 will be shifted from its position shown by Fig. 6 to the left hand end of its travel to cause the piston to return to the upper end of its stroke without making a complete downward stroke, such opening of the push button 147 will not reset the trip mechanism of either switch 131, although the lever 229 will be returned to its position shown by Fig. 8, because the notched end 239 of the lever 209 will be in position to cooperate with the projection 237 of

the lever 225 only if the solenoid 137 for operating each lever 209 is first deenergized by opening of the push buttons 21 and 23 to place the parts of the switches 131 and of the parts shown by the across the line diagrams in their positions shown by Fig. 4, which positions are exactly like that shown by Fig. 8 except that in the last mentioned figure the switch 143 is open. Thus should either push button 21 or 23 become short circuited it will be impossible by use of the push button 147 to reset the trip mechanism of that switch 131 which the short circuited push button controls. Only by correcting the short circuit, so that the solenoid 137 controlled by the short circuited push button may be deenergized, can the trip mechanism be reset.

It will be understood that within the scope of the appended claims wide deviations may be made from the form of the invention described without departing from the spirit of the invention.

I claim:

1. Control mechanism for a press or the like having a member which is reciprocated in a work stroke and a return stroke and also having mechanism governing the supply of energy thereto comprising a movable element which has a first position which provides a flow of energy effective to move said member in its return stroke and a second position which provides a flow of energy effective to move said member in its work stroke, said control mechanism comprising means for moving said element from its said first position to its said second position comprising circuit means controlled jointly by a pair of operator controlled switches which only when both are closed cause said circuit means to be energized for so moving said element, a separate circuit breaking means associated with each of said operator controlled switches tripped into open position when said element is so moved for rendering that associated switch inoperative to control said circuit means, and means for resetting each of said circuit breaking means controlled by opening of the operator controlled switch associated with it.

2. Control mechanism for a press or the like having a member which is reciprocated in a work stroke and a return stroke and also having mechanism governing the supply of energy thereto comprising a movable element which has a first position which provides a flow of energy effective to move said member in its return stroke and a second position which provides a flow of energy effective to move said member in its work stroke, said control mechanism comprising means for moving said element from its said first position to its said second position comprising circuit means controlled jointly by a pair of operator controlled switches which only when both are closed cause said circuit means to be energized for so moving said element, a separate circuit breaking means associated with each of said operator controlled switches tripped into open position when said element is so moved for rendering that associated switch inoperative to control said circuit means, means for causing movement of said element from its said second position to its said first position after it has been so moved to its said second position, and means for resetting each of said circuit breaking means operated jointly in response to the last mentioned movement of said element and the opening of the operator controlled switch associated with that circuit breaking means.

3. Control mechanism for a press or the like having a member which is reciprocated in a work stroke and a return stroke and also having mechanism governing the supply of energy thereto comprising a movable element which has a first position which provides a flow of energy effective to move said member in its return stroke and a second position which provides a flow of energy effective to move said member in its work stroke, 10 said control mechanism comprising means for normally maintaining said element in its said first position for holding said member at the end of its return stroke, operating means for said element comprising a circuit energized by closure of a pair of switches in series for moving said element from its said first position to its said second position for causing a work stroke of said member, means for tripping said switches, and means for establishing a holding circuit for said operating means in shunt with said switches, upon said first mentioned circuit being deenergized; means for automatically interrupting said holding circuit when said member reaches the end portion of its work stroke for causing movement of said element from its said second position to its said first position for returning said member to the end of its return stroke, and means for separately closing said switches comprising a separate circuit for each and a pair of operator controlled switches, each of said latter for separately controlling those circuits, each operator controlled switch when closed energizing the circuit controlled by it for closing the associated switch of said pair of switches, each operator controlled switch when released by the operator automatically opening for deenergizing the circuit controlled by it, the means for tripping said switches being operated into reset position jointly in response to deenergization of both 30 of said circuits controlled by said operator controlled switches and the interruption of said holding circuit.

4. Control mechanism for a press or the like according to claim 3 in which each operator controlled switch is a four-pole single-throw switch, the means for closing the switches of the pair of switches in series comprising a separate solenoid for each of those switches energized by closure of said operator controlled switches, respectively, the terminals of each solenoid being connected to a pair of the poles of said operator controlled switch and the other pair of said poles being connected to opposite sides of a line for isolating the solenoid from both sides of said line when the operator controlled switch is open.

5. Control mechanism for a press or the like according to claim 3 in which a normally closed switch is included in the holding circuit, which switch when opened interrupts the holding circuit for moving the element from its second position to its first position, said holding circuit and the circuits controlled by the operator controlled switches being connected across the line in parallel.

6. Control mechanism for a press or the like having a member which is reciprocated in a work stroke and a return stroke and also having mechanism governing the supply of energy thereto comprising a movable element which has a first position which provides a flow of energy effective to move said member in its return stroke and a second position which provides a flow of energy effective to move said member in its work stroke, said control mechanism comprising means for normally maintaining said element in its said

first position for holding said member at the end of its return stroke, operating means for said element having a controlling circuit comprising a pair of switches in series which when closed cause said operating means to move said element from its said first position to its said second position, a separate operating means for each of said pair of switches comprising a circuit having an operator controlled switch normally biased into open position and which when closed by the operator causes the last mentioned operating means to close such switch of said pair of switches, a separate trip mechanism for each switch of said pair of switches for automatically tripping the switch into open position when both switches of said pair of switches are closed for causing said element to move from its said first position to its said second position, and resetting means for each trip mechanism controlled jointly by movement of said element from its said second position to its said first position and deenergization of the circuit for the operating means for that switch.

7. Control mechanism for a press or the like having a member which is reciprocated in a work stroke and a return stroke and also having mechanism governing the supply of energy thereto comprising a movable element which has a first position which provides a flow of energy effective to move said member in its return stroke and a second position which provides a flow of energy effective to move said member in its work stroke, said control mechanism comprising means for normally maintaining said element in its said first position for holding said member at the end of its return stroke, operating means for said element having a controlling circuit comprising a pair of switches in series which when closed cause said operating means to move said element from its said first position to its said second position, a separate operating means for each of said pair of switches comprising a circuit having an operator controlled switch normally biased into open position and which when closed by the operator causes the last mentioned operating means to close such switch of said pair of switches, a separate trip mechanism for each switch of said pair of switches for automatically tripping the switch into open position when both switches of said pair of switches are closed for causing said element to move from its said first position to its said second position, and resetting means for each trip mechanism controlled jointly by deenergization of both said controlling circuit and said circuit for the operating means for the switch adapted to be tripped by the trip mechanism.

8. Control mechanism for a press or the like having a member which is reciprocated in a work stroke and a return stroke and also having mechanism governing the supply of energy thereto comprising a movable element which has a first position which provides a flow of energy effective to move said member in its return stroke and a second position which provides a flow of energy effective to move said member in its work stroke, said control mechanism comprising means for normally maintaining said element in its said first position for holding said member at the end of its return stroke, operator controlled means for moving said element into its said second position when said member is at the end of its return stroke, automatic means for moving said element into its said first position when said member is at the end of its work stroke, said

operator controlled means comprising a circuit having a pair of switches connected in series, which circuit when said switches are both closed causes said operator controlled means to move said element into its said second position, said operator controlled means also comprising separate circuits each for operating a separate one of said pair of switches, each of said separate circuits being controlled by an operator controlled switch which when closed by the operator energizes the circuit having the same to cause closing of the associated switch of said pair of switches, a separate trip means associated with each switch of said pair of switches for automatically tripping that switch upon closure of both of those switches, and means for separately resetting said trip means upon both the operator controlled switch controlling the circuit for closing the associated switch of said pair of switches being opened and said automatic means acting to move the element from its said second position to its said first position.

9. Control mechanism for a press or the like having a member which is reciprocated in a work stroke and a return stroke and also having mechanism governing the supply of energy thereto comprising a movable element which has a first position which provides a flow of energy effective to move said member in its return stroke and a second position which provides a flow of energy effective to move said member in its work stroke, said control mechanism comprising means for normally maintaining said element in its said first position for holding said member at the end of its return stroke, operating means for said element having a controlling circuit comprising a pair of switches in series which when closed cause said operating means to move said element from its said first position to its said second position, a separate operating means for each of said pair of switches comprising a circuit having an operator controlled switch normally biased into open position and which when closed by the operator causes the last mentioned operating means to close such switch of said pair of switches, a separate trip mechanism for each switch of said pair of switches, each trip mechanism comprising a first part and a second part each movable into and out of a position in which they cooperate with each other for rendering said operating means for the switch operative and inoperative, respectively, to close said switch, the said first part when moved out of such position tripping the switch from closed to open position, said controlling circuit for said operating means for said element comprising a holding circuit for shunting said pair of switches when the latter are in open position and said element is in its said second position, a normally closed switch connected for operatively interrupting said holding circuit when that switch is opened, means for opening the last mentioned switch in response to movement of said member to the end of its work stroke for opening said holding circuit to interrupt the controlling circuit for the operating means for the element so as to cause said element to move from its said second position into its said first position and to cause said first part of each trip mechanism to move into its position in which it is adapted to cooperate with said second part of said mechanism, and means operated only in response to deenergization of said controlling circuit for closing each switch of said pair of switches for moving said second part of each of said mechanisms into its position in which it

cooperates with said first part of that mechanism.

10. Control mechanism for a press or the like having a member which is reciprocated in a work stroke and a return stroke and also having mechanism governing the supply of energy thereto comprising a spring-pressed movable element which has a first position to which it is moved by the spring, in which position it provides a flow of energy effective to move said member in its return stroke and a second position which provides a flow of energy effective to move said member in its work stroke, said control mechanism comprising a solenoid for moving said element against the resistance of the spring to its second position, circuit means comprising a switch for energizing said solenoid when said switch is closed, a second spring for normally holding said switch in open position, a second solenoid for moving said switch into closed position against the resistance of said second spring, circuit means for energizing said second solenoid for so moving said switch into closed position comprising a second and a third switch in series with said second solenoid, circuit means comprising separate solenoids for operating said second and third switches, respectively, into closed position for energizing said second solenoid whereby to cause the latter to close the first mentioned switch for energizing the element operating solenoid for causing the latter to move the element to its said opposite end of its travel, circuit means having separate operator controlled push buttons for, when closed, separately connecting said solenoids for said second and third switches in parallel across a line for separately energizing those solenoids, separate trip mechanisms associated with said second and third switches, respectively, each trip mechanism having means operated in response to energization of said element operating solenoid for tripping such associated switch into open position and each having means operated in response to deenergization of both said element operating solenoid and the solenoid for such associated switch for resetting said mechanism to permit the associated switch again to be closed by energization of its solenoid, a holding circuit comprising a fourth switch operated into closed position, by said second solenoid when the latter is energized upon said push buttons being closed by the operator, for establishing a shunt connection around said second and third switches for continuing the energization of said second solenoid when said second and third switches are so tripped into open position, a fifth switch in series with said second solenoid adapted to be moved into open position by movement of said member to the portion of its work stroke for deenergizing said second solenoid and consequently the element operating solenoid for resetting said trip mechanisms when the solenoids for said second and third switches are deenergized by the operator permitting said push buttons to open.

11. Control mechanism for a press or the like according to claim 10 in which the solenoid for each of the second and third switches has an associated movable armature, a member operated by movement of said armature in one direction as a result of energization of said solenoid for swinging said member about a fulcrum for closing the switch, the element operating solenoid having an associated movable armature, mechanism operated in response to movement of the last mentioned armature in one direction as

a result of deenergization of said element operating solenoid for moving said fulcrum into a position in which it is adapted to be in cooperating relation with said member and for moving said fulcrum out of such position for tripping the switch into open position when said last mentioned armature is moved in the opposite direction as a result of energization of said element operating solenoid upon closure of said switch, 5 said mechanism for swinging said member being operated by movement of the first mentioned armature in the opposite direction as a result of deenergization of the first mentioned solenoid for moving said member into a position in which it is adapted to be in cooperating relation with said fulcrum.

12. Control mechanism for a press or the like according to claim 9 in which the operating means for each switch of the pair of switches connected in series comprises a solenoid, while each operator controlled switch is in circuit with a separate one of said solenoids for energizing it when the operator controlled switch is closed, the operator controlled switches each being a four-pole single-throw switch, the terminals of each solenoid being connected to a pair of said poles of the operator controlled switch in circuit with it while the other pair of poles are severally connected to opposite sides of the line for isolating the solenoid from the line when the operator controlled switch is open.

13. Control mechanism for a press or the like according to claim 9 in which the holding circuit also has a normally closed operator controlled switch which when opened interrupts said holding circuit, the holding circuit and the circuits of the separate operating means for the switches of the pair of switches connected in series being connected in parallel across the line.

14. Control mechanism for a press or the like according to claim 9 in which the operating means for each switch of the pair of switches connected in series comprises a solenoid, while each operator controlled switch is in circuit with a separate one of said solenoids for energizing it when the operator controlled switch is closed, the operator controlled switches each being a four-pole single-throw switch, the terminals of each solenoid being connected to a pair of said poles of the operator controlled switch in circuit with it while the other pair of poles are severally connected to opposite sides of the line for isolating the solenoid from the line when the operator controlled switch is open, the holding circuit also having a normally closed operator controlled switch which when opened interrupts said holding circuit, the holding circuit and the circuits controlled by the first mentioned operator controlled switches being connected in parallel across the line.
